UNITED STATES PATENT OFFICE.

LAURENT NAUDIN, OF PARIS, FRANCE, ASSIGNOR TO LA SOCIETE
FRANCAISE DE LA VISCOSE, OF PARIS, FRANCE.

APPARATUS FOR TREATING VISCOSE.

SPECIFICATION forming part of Letters Patent No. 773,412, dated October 25, 1904.

Application filed March 31, 1904. Serial No. 201,022. (No model.)

To all whom it may concern:

Be it known that I, LAURENT NAUDIN, engineer, a citizen of the French Republic, residing at Paris, France, have invented certain new and useful Improvements in Apparatus for Treating Viscose, of which the following is a specification.

It is known that a gloss or brilliancy similar to that of silk can be obtained on filaments of viscose by effecting under tension the fixing of the filament by means of a dilute mineral acid—that is to say, that the filament must be subjected simultaneously to a tractive stress or strain and to the action of the acid. Up to the present this tractive stress or strain has been produced by hand. Consequently it has not always been possible to insure complete uniformity in the treatment and in the resulting effect, so that some parts of a skein of filaments have acquired a better gloss than other parts of the same skein. Now this invention has for its object to provide apparatus which is intended to remedy this drawback.

In the accompanying drawings, Figure 1 is a longitudinal section of the apparatus. Fig. 2 is a transversal section.

A convenient constructional example of the improved apparatus comprises a vessel 1, in which are arranged one above the other two parallel arms or shafts 2 3, provided with drums or wooden rollers 4 5, which are capable of revolving readily on their shafts and are adapted to carry skeins of viscose filaments. At or in the upper part of the vessel there is provided a spraying or sprinkling pipe 6 for discharging dilute sulfuric acid into the vessel and onto the skeins. The lower shaft 3 is connected to the rod of a piston 7, operating in a hydraulic or other cylinder 7. The latter is fitted with inlet and outlet valves, which are arranged to open and close automatically. The cylinder 7 is also fitted at each end with an inlet-cock and an outlet-cock. The said piston is preferably actuated by water under pressure; but it is obvious that it might also be actuated by compressed air or even by means of a vacuum.

In using the improved apparatus first the lower inlet-cock 8 and the upper outlet-cock 9

are opened. Fluid enters through the lower inlet-cock 8 and is discharged through the upper outlet-cock 9. The piston rises and raises the lower shaft 3, thus allowing the skeins to be placed in position over the drums or rollers carried by the two shafts. Then the lower inlet-cock 8 is closed and the lower outlet-cock 10 is opened. The lower shaft moves down and stretches the skein by its own weight.

The reference character 11 denotes a driving-shaft carrying a worm 11^a, which meshes with the worm-gear 11^b, fixed upon the cam-shaft 12, the latter being driven through the medium of said worm 11^a and worm-gear 11^b when the driving-shaft 11 is operated. Fixed upon the shaft 12 are the cams 13 14. The former is termed the "primary" and the latter the "secondary." The cams 13 14 are adapted to impart a vertical movement to a pair of shifting rods 13^a 14^a. The cam 13 actuates the rod 13^a, and the cam 14 actuates the rod 14^a. The rods 13^a 14^a each operate through a pair of guide-keepers 14^c, and the said rods 13^a 14^a are connected at their upper ends to the cocks 9 and 15. The connection between the rod 13^a and the cock 9 is in the form of a link 13^b, and the connection between the rod 14^a and the cock 15 is in the form of a link 14^b.

When the shaft 11 drives the cam-shaft 12 through the medium of the worm 11^a and the worm-gear 11^b, the primary cam through the medium of the rod 13^a and the link 13^b closes the outlet-cock 9 and the secondary cam 14 through the medium of the rod 14^a and link 14^b opens the upper inlet-cock 15. The skeins are thereby stretched by hydraulic or other pressure during a period of time which is determined by the duration of the operation of the cams. When the primary and secondary cams 13 14 have completed their operation, the upper inlet-cock 15 closes and the upper outlet-cock 9 opens. In this position of the cocks the skeins are stretched solely by the weight of the roller 5 on the lower shaft. At this moment a tertiary cam 16, carried by the shaft 12, tilts a lever 17 in such a manner as to cause a pulley 18, which is mounted loose on the driving-shaft 11, to come into engagement with said shaft 11.

The pulley 18 drives a worm-shaft 19, which causes the upper shaft 2 to rotate. At the same time a pulley 20 on the last-mentioned worm-shaft 19 and a pulley 21 on another worm-shaft, 22, causes the lower shaft 3 to rotate. This combined motion of the upper and lower shafts causes the skein to change its position and by this means insures a uniform action of the sulfuric acid upon the various portions 10 of the filament. When the tertiary cam 16 has completed its operation, the pulley 18 on the driving-shaft is disengaged from its shaft by the action of a counterweight 23, so that the upper and lower shafts 2, 3 cease rotating 15 and the primary and secondary cams 13, 14 operate the upper and lower outlet-cocks 9 and 15 in the same manner as hereinbefore described. The skeins are thus again placed under tension, as set forth. This alternate 20 operation of tension and shifting of the skeins may be repeated as often as desired.

In order to stop the treatment of the skeins, it is sufficient to disengage the driving-shaft 11, to cause the lower shaft to move upwardly 25 by hydraulic or other pressure, to remove the skeins which have been fixed or treated, and to place fresh skeins in their place.

Having thus described and ascertained the nature of my invention and in what manner 30 the same may be performed, I declare that what I claim is—

1. An apparatus for fixing skeins of viscose having a vessel, two parallel shafts arranged in this vessel for carrying the skeins, and 35 means for alternatively increasing the distance between and for rotating said shafts, substantially as described.

2. An apparatus for fixing skeins of viscose having a vessel two parallel shafts in this vessel for carrying the skeins, a cylinder, a fluid-operated piston in said cylinder carrying the lower shaft, inlet and outlet cocks for the 40 said cylinder and cams on a cam-shaft for closing or opening these cocks, and for engaging or disengaging the shafts with the driving-shaft, substantially as described.

3. An apparatus for treating skeins of viscose comprising a vessel, a sulfuric-acid-spray pipe arranged therein, a pair of intermittently- 50 rotatable skein-carrying shafts mounted in said vessel below the said pipe, means connected with one of said shafts for imparting an intermittent vertical movement thereto, and means connected with said shafts for imparting an intermittent rotary movement thereto.

4. An apparatus for treating skeins of viscose comprising a vessel, a sulfuric-acid-spray pipe arranged therein, a pair of intermittently- 55 rotatable skein-carrying shafts mounted in said vessel below said pipe, a fluid-operated means connected with one of said shafts for

imparting an intermittent vertical movement thereto, and means connected with said shaft for imparting an intermittent rotary movement thereto.

65

5. An apparatus for treating skeins of viscose involving a pair of rotatable skein-carrying shafts, a rotatable cam-shaft, primary, secondary and tertiary cams carried thereby, and means engaged and operated by said cams 70 for imparting an intermittent vertical movement to one of said skein-carrying shafts and for intermittently rotating said pair of skein-carrying shafts simultaneously.

6. An apparatus for treating skeins of viscose involving a pair of parallel skein-carrying shafts, and means for automatically and intermittently increasing the distance between and rotating said shafts.

7. An apparatus for treating skeins of viscose involving a pair of skein-carrying shafts, a fluid-operated means for increasing the distance between said shafts, and means for intermittently rotating said shafts.

8. An apparatus for treating skeins of viscose involving a pair of skein-carrying shafts, a fluid-pressure-operated means for automatically and intermittently increasing the distance between said shafts, and means for automatically and intermittently rotating said 90 shafts.

9. An apparatus for treating skeins of viscose involving a pair of skein-carrying shafts, a rotatable cam-shaft, primary, secondary and tertiary cams carried thereby, means engaged 95 and operated by said primary and secondary cams for increasing the distance between said shafts, and means engaged and operated by said tertiary cam for intermittently rotating said pair of shafts simultaneously.

100

10. An apparatus for treating skeins of viscose involving a pair of skein-carrying shafts, a fluid-operated means connected to one of said shafts and adapted when operated to increase the distance between the said shafts, a rotatable cam-shaft, primary, secondary and tertiary cams carried thereby, inlet and outlet valve mechanisms adapted when operated to cause the operation of said fluid-operated means, means engaged and operated by said primary and secondary cams for operating said mechanisms, and means engaged and operated by said tertiary cam for causing a rotary movement to be imparted to said shafts.

105

In testimony whereof I have hereunto set 110 my hand in presence of two subscribing witnesses.

LAURENT NAUDIN.
